US00D926158S

(12) **United States Design Patent** (10) **Patent No.:** **US D926,158 S**
(45) **Date of Patent:** **** Jul. 27, 2021**

(54) **SPEAKER BOX**

(71) Applicant: **Sphere Technology LLC**, Tottori (JP)

(72) Inventor: **Masanori Hirotani**, Tottori (JP)

(73) Assignee: **Sphere Technology LLC**, Tottori (JP)

(**) Term: **15 Years**

(21) Appl. No.: **35/509,264**

(22) Filed: **Jun. 10, 2019**

(80) **Hague Agreement Data**

Int. Filing Date: **Jun. 10, 2019**

Int. Reg. No.: **DM/207600**

Int. Reg. Date: **Jun. 10, 2019**

Int. Reg. Pub. Date: **May 8, 2020**

(30) **Foreign Application Priority Data**

Dec. 10, 2018 (JP) 2018-026850
